ABSTRACT

An incandescent filament lamp having an envelope closed with a wedge-shaped pinch seal and a cap disposed about the seal. Cuts are made in the cap and portions thus freed are bent inwards to provide a seating structure for the seal.

5 Claims, 3 Drawing Figures

FIG. 1

INCANDESCENT FILAMENT LAMPS

This is a continuation of application Ser. No. 827,497, filed May 23, 1969, now abandoned.

The present invention relates to the provision of cap connectors for the pinch sealed envelopes of lamps, such as, for example, fluorescent lamps, discharge lamps and incandescent filament lamps.

It has been proposed that lamp envelopes should be closed with a pinch seal through which terminal leads for connections to filaments or electrodes would be sealed. Such a pinch seal could be plugged directly into a socket thus dispensing with the need to seal a conductive cap onto the end of the envelope. However, the introduction of such a lamp would require replacement of all existing sockets by sockets adapted to receive pinch sealed lamps. This amount of obsolescence would not be acceptable in, for example, the field of domestic lighting, where it would involve the replacement of many millions of light fittings. It is however clear that considerable manufacturing advantages could be obtained if lamps were pinch sealed.

According to the present invention there is provided a lamp having an envelope closed by a pinch seal through which terminal leads for the lamp extend and a cap within which are provided one or more seating structures cooperating with the pinch seal to seat the envelope in the cap, portions of the terminal leads extending beyond the envelope being secured to the cap so as to prevent the envelope from moving axially relative to the cap.

In a preferred form of the invention an incandescent filament lamp includes an envelope formed with a wedge-shaped pressed pinch seal, the thin end of the seal being the end remote from the filament, and a cap within which are disposed one or more seating structures which co-operate with the sides of the wedge-shaped seal to seat the envelope in the cap.

Advantageously, the pinch seal tapers on one or both sides from its centre portion towards one or both of its edges.

The seating structure may include portions of a shape complementary to the shape of the seal whereby a face to face contact between the seal and the seating structure is maintained when the envelope is seated in the cap.

The seating structures may be constituted by internally extending lugs formed by making cuts in the cap and bending inwards the section of the cap thus freed.

Embodiments of the invention will now be described, by way of example with reference to the accompanying drawings, in which:

FIG. 1 is an exploded view of a first embodiment of the invention showing the cap and the envelope,

FIG. 2 is a side elevation in part section of a second embodiment,

FIG. 3 is a plan along III-III in FIG. 2,

In FIG. 1 of the drawings, a glass envelope 11 has a bulbous portion 12 and a tapering portion 13. The tapering portion 13 has a wedge-shaped pressed pinch seal 14. Two leads 15 for the filament 16 of the lamp extend through the closed end of the seal 14. A cap 17 in which the envelope is seated has a base 18 and a side-wall 19, two pairs of lugs 21, 22 and 23, 24 respectively securing the envelope 11 in position in the cap 17. Each lug 21, 22, 23 and 24 is formed by making a V-shaped cut in the side wall 19 and bending the freed

section inwardly along the line joining the ends of the arms of the V-shaped cut.

The lugs 21, 22 and 23, 24 thus form seatings that co-operate with the sides of the pinch seal 14 of the envelope 11. The lugs of each pair 21, 22 and 23, 24 are closer together at their ends nearer the closed end of the cap 17.

The lead wires 15 pass through holes (not shown) in the base 18 of the cap 17, and are soldered or welded to the cap 17. The lugs 21 to 24 prevent rotational movement of the envelope and axial movement is prevented by the securing of the lead wires 15 to the cap 17.

The above example relates to one shape of lugs. It is clear that other configurations of the lugs are possible, and one alternative configuration is shown in FIGS. 2 and 3. In FIGS. 2 and 3 each part is given the same reference numeral as the corresponding part in FIG. 1.

The lamp comprises an envelope 11 having a tapering portion 13 with a wedge-shaped pressed pinch seal 14. Two leads 15 for the filament (not shown) extend through the closed end of the seal. The envelope is mounted in a cap 17 and seated in the cap 17 by two pairs of lugs 21, 22 and 23, 24 respectively. The lugs are flat and have a complementary taper to the taper of the seal 14.

The leads 15 pass through holes in the base 18 of the cap 17 and are soldered or welded to the cap. The lead wires can be stiffened-up to make this joint more secure.

The caps shown in the drawings are bayonet caps; however it is clear that other types of caps could be used, e.g. Edison screw caps, or 2 pin caps.

We claim:

1. An electric lamp comprising an envelope having a pinch seal at one end thereof; a pair of lead wires extending from the inside to the outside of said envelope, at least one of said lead wires being sealed through and extending beyond said pinch seal, a cap disposed about said pinch seal, seating means including a plurality of lugs extending inwardly of said cap and abutting said pinch seal to prevent rotational movement of said envelope, said at least one lead wire being fixedly attached near its outer end to said cap to hold said seal against said lugs and to prevent said envelope from moving axially relative to said cap.

2. A lamp as claimed in claim 1, wherein said pinch seal tapers on at least one side from its centre towards at least one edge, said cap has a closed end, and said lugs comprise two pairs of lugs, the lugs of each pair being closer together at their ends nearer the closed end of said cap.

3. A lamp as claimed in claim 1, wherein portions of said lugs have a shape complementary to the shape of said pinch seal whereby a face to face contact is maintained between said seal and said lug portions.

4. A lamp as claimed in claim 1, wherein said lugs are formed by making cuts in said cap and bending inwards the sections of said cap thus freed.

5. An incandescent filament lamp comprising an envelope having a wedge-shaped pinch seal at one end thereof, the thin end of the wedge being the end remote from the filament;

a pair of lead wires sealed through said pinch seal in spaced apart relationship to one another and extending beyond said pinch seal, said lead wires being connected at their inner ends to said filament,
 a cap disposed about said pinch seal; seating structures including a plurality of lugs having

flat sides extending inwardly of said cap and abutting the sides of said wedge shaped pinch seal to prevent rotational movement of said envelope, said lead wires being fixedly attached to said cap to hold said seal against said lugs and to prevent said envelope from moving axially relative to said cap.
